LATCH STRUCTURE

Robert Pauli Scherer, Detroit, Mich., assignor to
 R. P. Scherer Corporation, Detroit, Mich., a corporation of Michigan

Application June 24, 1950, Serial No. 170,102

8 Claims. (Cl. 74—2)

1

This invention relates to a latch structure particularly designed for a hypo jet injector of the kind shown in my copending application, Serial No. 170,101 filed June 24, 1950, but likewise useable wherever a movable element biased to move in one direction is to be latched against such movement.

Several problems presented themselves in the design of a latch structure for a hypo jet injector:

(1) To make an instantaneously releasable support for a heavy load.

(2) To make such a support capable of repeated functioning without undue wear.

(3) To make such a support releasable by a relatively light releasing force which releasing force remains consistent throughout manufacturing variations and over an extended period of use.

(4) To make such a support and releasing means which are compact and capable of being readily reset.

To solve these several problems, research developed the following considerations:

(1) A combination of primary support and secondary support for the heavy load.

(2) A high lever ratio between the primary support and the secondary support.

(3) A primary support off which the load "rolls" instead of the support being slipped out from under the load.

Therefore a "latch roll" was adopted having a lever arrangement entirely within the diameter of the roll which contributes to compactness, and the secondary support adopted was a pivoted latch for the latch roll. The latch has a retrograde camming action on the latch roll to aid in the ease of release, the parts being so arranged that relatching is accomplished by simply restoring the load carrying part to an original position with respect to the primary support, the primary and secondary supports (or latch roll and latch) returning automatically to latched position after which the load can be imposed on the load carrying part and thereby on the primary support.

One object of the present invention therefore is to provide a latch structure which in spite of a heavy load imposed thereon, such as springs or the like tending to move the movable element, is nevertheless readily releasable by light pressure on a release button at the will of the operator.

Another object is to provide a latch structure in which a latch roll constitutes the primary support and coacts with a shoulder of a movable

2

element to hold the movable element against movement due to a bias acting thereon, together with a latch that constitutes the secondary support and releases the latch roll so that it may rotate and thereby release the movable element by a rolling action without breaking down the latching edges which coact between the movable element and the latch roll.

Still another object is to provide a latch roll so designed in relation to its axis of rotation, and the axis being so related to a shoulder of the movable element, that there is a positive tendency for the latch roll to be rotated to the unlatching position due to the bias which acts on the movable element, thereby making possible the use of a latch of such design that it may be released by the application of a relatively light force.

A further object is to provide a novel type of latch mechanism for holding springs or other driving means in loaded condition in such a manner that their store of energy may be instantaneously and easily released without appreciable wear on the latch mechanism.

A more specific object is to provide a latch structure in the form of a latch roll having a latching shoulder engaged by a latching shoulder of a movable element which is biased to move in one direction, the engagement being to one side of the axis of rotation of the latch roll. A latch for the latch roll is then provided having a surface engagement therewith which is shaped to have a slight tendency to be self-releasing, such self-releasing tendency, however, being of less magnitude than the holding action of the latch-restoring springs so as to reduce the pressure required for release to a predetermined small value.

With these and other objects in view, my invention consists in the construction, arrangement and combination of the various parts of my latch structure, whereby the objects contemplated are attained, as hereinafter more fully set forth, pointed out in my claims and illustrated in the accompanying drawings, wherein:

Figure 1 is an enlarged sectional view through a hypo jet injector of the kind shown in my above-mentioned copending application showing the rear half or release button end thereof and illustrating the latch structure of the present invention in association therewith.

Figure 2 is a similar sectional view, this figure being of the ampule containing end of the injector and a continuation of the right hand end 55 of Figure 1, both Figures 1 and 2 showing the

parts in latched position and ready for the latch structure to be released.

Figures 3 and 4 are detail sectional views on the lines 3—3 and 4—4 respectively of Figure 1.

Figure 5 is a side elevation of that portion of Figure 1 adjacent the section lines 3—3 and 4—4 showing the latch housing, a latch in dotted lines, and the end of the latch roll together with portions thereof also dotted.

Figure 6 is a sectional view similar to the left hand end of Figure 1 showing the latch released, the latch roll partially rotated by movement of the movable element, which it normally retains against movement and, by dotted lines, a final position of the latch roll.

Figure 7 is a fragmentary sectional view showing the latch in side elevation and the latch roll in the dotted position of Figure 6 during the latching of the hypo jet injector.

Figure 8 is an enlarged sectional view showing the latch mechanism in a position just prior to being completely latched; and

Figure 9 is a still more greatly enlarged sectional view showing the parts in the completely latched position and illustrating constructional features in detail.

First describing the hypo jet injector shown on the accompanying drawings and particularly Figures 1 and 2 in a general way, I have used the reference numeral 20 to indicate a body for most of the mechanism of the injector. The body 20 has threaded on the forward end thereof a dosage sleeve 30, and a winding sleeve 40 is rotatable on the rear end thereof as shown in Figures 1 and 2 respectively. The sleeve 40 has an inturned flange 41 coacting with an annular shoulder 22 on the body 20 to prevent longitudinal movement in one direction relative to the body. A latch housing 50 is screwed into the rear end of the winding sleeve 40 with a thrust bearing assembly 23 interposed between the body and the latch housing.

A release button cap 60 is threaded on the latch housing 50 and the entire assembly of winding sleeve 40, latch housing 50, and cap 60 is held in the assembled relation by a set screw 42 engaging all three parts and sealed in place, as shown in Figure 3.

The dosage sleeve 30 has threaded on its forward end an ampule holder 70 adapted to receive an ampule 71 having medicament 72 therein and a cup-like follower 73 formed of "Neoprene" or the like (see Figure 2). The ampule is provided with a reduced discharge nozzle 74 perforated by a minute or capillary discharge orifice 75. The ampule holder is covered by resilient nose 76 such as one of "Neoprene" or the like.

The internal mechanism of the hypo jet injector includes a primary plunger 80, a secondary plunger 90 which is tubular in character and has a disc-like portion 92, and mechanism for propelling these plungers and thereby the follower 73 forwardly in the ampule 71 to discharge the medicament 72 through the orifice 75 thereof as fully explained in my copending application above referred to.

The mechanism mentioned in the preceding paragraph comprises a nut 100, a screw 110, and a plurality of power springs 111. The nut is 70 sleeve-like in character and has a disc-like head 102 provided with spring seats for the springs 111 which springs, at their opposite ends, seat against a partition 112 of the body 20.

The nut 100 has threads 104 at its left end as

shown in Figure 1 which cooperate with the threads of the screw 110. The screw at its left end as shown in Figure 1 is provided with a head 115 providing a latching shoulder 116. The screw head 115 terminates in a bifurcated portion which results in a pair of spaced blades 117, the head with its blades being slidable in a square opening 52 of the latch housing 50 (see also Figures 3 and 4).

As illustrated in Figure 3, the latch housing is provided with a cross slot 53 in which a secondary support or latch 54 is pivotally mounted. For this purpose a pivot pin 59 is a press fit in the latch and has its ends rotatable in the latch housing. The latch substantially spans the width of the slot 53 and the space between the blades 117 of the screw and is of the shape shown in Figure 1 having a latching shoulder 55 and a spring socket 56. A latch spring 57 has one end seated in the socket and its other end seated in an opposing socket 58 of the latch housing for tending to rotate the latch counter-clockwise.

Slidably mounted in the release button cap 60 is a release button 61 having a cross bar 62 attached thereto and slidable in the slot 53 of the latch housing 50 and the space between the blades 117 of the screw 110 back of the latch 54. When this button is depressed, as in Figure 6, it rocks the latch 54 against the bias of the spring 57 as shown.

A primary support or latch roll 63 is provided having end portions 64 and 65 rotatable in the latch housing (see Figure 4), and a latch portion between the end portions which is of the cross-sectional shape shown best in Figure 9. This latch portion is of a particular shape having a first shoulder 66, a second shoulder 67, and a third shoulder 68, the purpose of which will hereinafter be described. The shoulders 66 and 67 extend substantially radially of the axis 69 of the latch roll and the shoulder 68 is slightly less than a 90 degree angle to the shoulder 66. The shoulder 67 has a corner cut off at 67a and the shoulder 66 is rounded at its upper end as shown at 66a. As shown in Figures 1 and 9, the shoulder 67 is adapted to be engaged by the latching shoulder 55 of the latch 54, and the shoulder 66 is adapted to engage the latching shoulder 116 of the screw 110.

The latch roll 63 (Figures 4 and 5) is biased to rotate counter-clockwise in Figures 1 and 5 to 9 by a latch spring 77 wound around a reduced portion 78 of the latch roll and having one end received in a hole 31 thereof as shown by dotted lines in Figure 5 and its other end hooked in a hole 32 of the latch housing 50.

The axis of rotation 69 (see Figures 8 and 9) of the latch roll lies slightly outside line of lower surface of head 115 or slightly beyond the outer limit of the path of travel of this surface as shown by the horizontal and vertical center lines so there is a positive tendency as the springs 111 bias the screw 110 toward the right as indicated by the arrow a to rotate the latch roll clockwise but it is prevented from doing so by the second shoulder 67 engaging the latching shoulder 55 of the latch 54 until such time as the latch is released by depressing the release button 61 as in Figure 6. Such an arrangement minimizes the required pressure to operate the release button yet provides a rugged holding shoulder against the expanding tendency of the power springs 111, and the shoulder 66 of the latch roll rolls out from under the shoulder 116 of the screw 110 when the latch is operated, thus

minimizing the wear between the latch roll and the shoulder 116 as distinguished from an ordinary latch which is pulled from beneath a shoulder with a resulting tendency to break down the edges of the latch and the shoulder. The rounding 66a of the shoulder 66 and the cut-off corner 115a aid in this respect.

Referring to Figure 9, due to the proximity of the axis 69 to the lower surface of the head 115, the shoulder 66 assumes but a small angle relative to this surface (dotted position) after the screw 110 is unlatched and while it is being moved in a direction opposite the arrow *a* during the relatching portion of a cycle of operation. This prevents the rounded edge 66a from gouging into the lower surface of the screw during relatching and the rounding 66a is also helpful for this purpose. Also during the relatching an incline 115b of the lower surface of the head 115 permits the latch roll 63 to be gradually rocked by the action of its spring 77 back to the position of Figure 8 so the latch 54 can be pivoted by its spring 57 to the latched position.

The latching shoulder 55 of the latch 54 (see Figure 9) is formed on a radius *R*, the center of which is indicated at 81. This center is so located relative to the center 82 of oscillation of the latch that the latching shoulder 55 constitutes a camming surface having a slight retrograde movement as obvious by comparing the arcs 83 and 84 formed on a radius *R'* from the center 82 and a radius *R* from the center 81. This reduces the pressure required on the release button 61 when it is manually depressed to the position of Figure 6. As an example, the thumb pressure required may be 2 or 3% of the total loading of the springs 111 or of course may be decreased or increased as desired. Obviously a retrograde camming surface will reduce the pressure required and the greater the offset of the center 81 from the center 82, the greater will be the retrograde movement as the latch is rotated clockwise for releasing the camming shoulder 55 from the latch roll shoulder 67 and vice-versa. While I have described my latch structure particularly designed for a hypo jet injector of the kind disclosed, it is operable in connection with any type of movable element biased in one direction and having a latching shoulder with which the latch roll may engage.

Practical operation

In the operation of the hypo jet injector disclosed, assuming the parts to be in the position of Figures 1 and 2, the ampule 71 is in place and the springs 111 are latched in their compressed condition and ready for release. Release is accomplished by depressing the release button 61 to the position shown in Figure 6 so that the latching shoulder 55 of the latch is out of engagement with the second shoulder 67 of the latch roll. The retrograde shape of the shoulder 55 produces a cam action which permits the roll to rotate clockwise slightly as obvious from an inspection of Figure 9 and particularly the arcs 83 and 84 until the corner 67a of the second shoulder 67 coincides with the upper corner of the latching shoulder 55 whereupon the corner 67a cams the latch out of the way due to the pressure of the power springs 111 tending to move the screw 110 toward the right as indicated by the arrow *a*. This tendency is translated to a clockwise tendency for rotation of the latch roll as indicated by the arrow *b* and that tendency results in rotation, for instance, to the solid line position shown in Figure 6 with the shoulder 75

116 nearly released from the shoulder 66, engaging the rounded edge 66a thereof at that time and finally when the latch roll is rotated to the dotted position of Figures 6 and 9 (the same position as shown solid in Figure 7) the screw 110 will be released and is traveling toward the right as indicated by the arrow *c* for actuating the primary and secondary plungers 80 and 90, the position at that time being shown by dotted lines in Figure 6. Figure 7 illustrates the final limit of movement of the screw 110 in the discharged condition of the ampule at which time the springs 111 are expanded as far as the instrument will permit them to be expanded.

15 After the injection has been completed, it is necessary to relatch the screw 110 on the latch roll 63 and lock the roll against rotation by the latch 54 before winding the springs 111. This is accomplished by rotating the winding sleeve 40 counter-clockwise as far as possible which causes the screw to be screwed backwardly with relation to the nut, the nut remaining in its forward position and the screw finally assuming the position shown in Figure 8, its total movement starting at the position shown in Figure 7. It will be noted that the shoulder 116 of the screw has passed the shoulder 66 of the latch roll which permits the spring 77 of the roll to rotate the roll from the position of Figure 7 to the position of Figure 8 with the right hand edge of the shoulder 63 stopped against the reduced portion of the cocking screw at the bottom of the shoulder 116. This rotation of the latch roll also permits the spring 57 of the latch 54 to rock it from the position of Figure 7 to the position of Figure 8 behind the shoulder 67.

To accomplish the final latching of the screw 110 (see Figure 1), the winding sleeve 40 is rotated clockwise which will advance the screw back into the nut 100 until the shoulder 116 of the screw engages the shoulder 66 of the latch roll and rotates the latch roll clockwise from the position of Figure 8 to the position of Figures 1 and 9, such rotation of course being stopped by the shoulder 67 engaging the shoulder 55 as illustrated. At that time the cut-back incline 115b insures that the shoulder 116 will engage the shoulder 66 to a predetermined distance from the axis 69 to provide the proper leverage necessary to insure rotation of the latch roll 63 under the action of the springs 111 without any possibility of rotation of the roll stopping before unlatching has been completed as might be the case if the cut-back incline were not provided. It will also be noted in Figure 9 that the shoulder 66 in the latched position of the parts is slightly inclined to the left to help in assuring engagement between 66 and 116 a predetermined distance from the axis 69 for the purpose of keeping the pressure necessary to operate the release button within predetermined limits.

Thereafter further rotation of the winding sleeve 40 produces compression of the power springs 111 because the screw 110 is held by the latch roll against forward movement and since the screw is rotating the nut will be retracted along its threads carrying with it the nut head 102 (Figure 2) against the forward ends of the springs, this head of course moving toward the partition 112 (Figure 1).

The springs 111 can thereafter be compressed as much as desired and the hypo jet injector is rendered operable for performing another injection by thumb pressure on the release button 61.

From the foregoing specification it will be

obvious that the relatively powerful springs 111 are latched in the compressed condition by an efficient latch roll and latch arrangement which operates with a minimum of wear so that it is capable of proper operation for many thousands of cycles without breakdown of the latching edges as may occur in many other types of latching devices. When the parts are in the position shown in Figure 9, the shoulders 68 and 116 are in contact at a point sufficiently far from the axis 69 of the latch roll 63 that the springs 111 are capable of overcoming all friction involved and rotation of the latch roll is assured. The slightly retrograde camming contour of the shoulder 55 makes the latch easy to release manually in spite of the heavy load of the springs 111 thereon. The degree of camming may be changed to get any desired proportion of release button pressure to power spring pressure.

Some changes may be made in the construction and arrangement of the parts of my latch structure without departing from the real spirit and purpose of my invention, and it is my intention to cover by my claims any modified forms of structure or use of mechanical equivalents which may be reasonably included within their scope.

I claim as my invention:

1. In a latch structure of the character disclosed, a movable element biased to move in one direction, and means to releasably hold said element against said movement comprising primary and secondary supports, said primary support being rotatable on an axis adjacent said movable element and having a pair of shoulders, one of said shoulders being closer to the axis of rotation than the other, said movable element having a shoulder engaging said one of said shoulders, and said secondary support engaging the other of said shoulders and being movable from engagement therewith, said one of said shoulders having a rounded edge over which the shoulder of said movable element rolls as said movable element is released from said primary support.

2. In a latch structure, a movable element biased to move in one direction, and means to releasably hold said element against said movement comprising primary and secondary supports, said primary support comprising a latch roll rotatable on an axis adjacent said movable element and having a pair of shoulders lying within the circumference of the roll, one of said shoulders being closer to the axis of rotation than the other, said movable element having a shoulder engaging said one of said shoulders, said latch roll being biased to rotate in a direction for engaging said one of said shoulders with said movable element shoulder and said secondary support comprising a pivoted latch engaging the other of said shoulders and having a camming action in relation thereto tending to release said pivoted latch from said latch roll.

3. A latch structure for a movable element biased to move in one direction, comprising primary and secondary supports, said primary support being rotatable in bearings adjacent said movable element and having a pair of shoulders within the bearing circumference, one of said shoulders being closer to the axis of rotation than the other, said movable element having a shoulder engaging said closer shoulder of said primary support, and said secondary support being pivoted and engaging the other of said shoulders with a camming face tending to release said pivoted support from said primary support, said closer

shoulder having a rounded edge over which the shoulder of said movable element rolls as said movable element is released from said primary support.

5 4. In a latch structure, an element biased to move in one direction, and means to releasably latch said element against such movement comprising a shoulder on said element at substantially right angles to said direction of movement, a latch roll rotatably mounted on an axis closely adjacent but beyond the outer boundary of the path of travel of said shoulder, said latch roll having a shoulder adapted in one position of rotation to engage said shoulder of said movable element and in another position of rotation to be swung out of the path of said shoulder of said movable element, and a latch having a slightly retrograde cam surface adapted to engage another shoulder of said latch roll to prevent rotation thereof until said latch is released.

10 5. In a latch structure of the character disclosed, an element biased to move in one direction, and means to releasably latch said element against such movement comprising a shoulder on said element, a latch roll rotatably mounted on an axis at substantially right angles to said direction of movement, said axis being closely adjacent but beyond the outer boundary of the path of travel of said shoulder, said latch roll having a rounded shoulder adapted in one position of rotation to engage said shoulder of said movable element and in another position of rotation to be swung out of the path of said shoulder of said movable element, and a pivoted latch adapted to engage another shoulder of said latch roll to prevent rotation thereof until said pivoted latch is manually released, the portion of said pivoted latch which engages said latch roll being slightly retrograde cam-shaped.

15 6. In a latch structure of the character disclosed, a movable element biased to move in one direction, and means to releasably hold said element against such movement comprising a shoulder on said element, a latch roll rotatably mounted on an axis closely adjacent but beyond the outer boundary of the path of movement of said shoulder, said latch roll having a shoulder within the circumference of the roll adapted in one position of rotation to engage said shoulder of said movable element and in another position of rotation to be swung clear of the path of said shoulder of said movable element, and a latch adapted to engage another shoulder of said latch roll within the circumference of the roll but farther from the center of rotation than said first shoulder of said latch roll to prevent rotation thereof until said latch is released.

20 7. In a latch structure, a movable element having a shoulder biased to move along a substantially straight path, a latch roll to prevent such movement, said latch roll having its axis slightly beyond the outer boundary of the path of movement of said shoulder along said substantially straight path and biased to rotate into said path, said latch roll having a first shoulder substantially radially thereof to engage said movable element shoulder, said first shoulder having a rounded edge over which the shoulder of said movable element rolls as said movable element is released from said first shoulder, said latch roll having a second shoulder substantially radially thereof, said first and second shoulders both being within the circumference of said latch 25 roll, a pivoted support having a cam surface op-

erable to normally engage said second shoulder on a line normal to said second shoulder, said cam surface being slightly retrograde with respect to a constant radius from the pivot axis of said support, and a release button engageable with said support to release it from said second shoulder.

8. In a latch structure, a movable element having a shoulder biased to move along a predetermined path, a latch roll to prevent such movement, said latch roll having its axis beyond the outer boundary of the path of movement of said shoulder along said path at a distance less than radius of said latch roll and biased to rotate into said path, said latch roll having a first shoulder to engage said movable element shoulder, a second shoulder adapted to be engaged by a latch, and a third shoulder to engage one side of said movable element in all positions thereof except when the first shoulder of the 20

latch roll and the shoulder of the movable element are in supporting relationship, means biasing said latch roll to rotate in a direction to affect such engagement of said third shoulder with said one side of said movable element, and a releasable latch for said second shoulder.
